LIQUID FUEL BURNER

Kemper P. Brace and Victor W. Kliesrath,
South Bend, Ind., assignors to International
Engineering Corporation, Chicago, Ill., a cor-
poration of Illinois

Application January 6, 1938, Serial No. 183,624

3 Claims. (Cl. 158—5)

This invention relates to liquid fuel burners and more particularly to vaporizing type burners for use with heating furnaces or the like.

The capacity of a vaporizing type burner is limited by the rate at which the oil or other liquid fuel can be vaporized and this rate is largely dependent upon the rate at which heat can be supplied to the vaporizing nozzle. Since air for combustion must flow through or around the nozzle it has a cooling influence tending to reduce the rate of vaporization.

We have found that the rate of vaporization can be increased by increasing the heating effect on the nozzle and by reducing the cooling effect 15 of the air supplied for combustion. This latter effect is preferably obtained by heating the air prior to its contact with the nozzle. It is accordingly one of the objects of the invention to provide a liquid fuel burner in which the rate 20 of vaporization of the fuel is increased to a maximum.

It is another object of the invention to provide a fuel burner for a furnace in which the air for combustion is heated by operation of the furnace 25 prior to contact with the nozzle.

Another object of the invention is to provide a liquid fuel burner in which there is a perforated firebox or shell around the nozzle to increase the heating effect on the nozzle. The fixed size of 30 this shell also in effect provides a firebox of fixed size for and in a definite relationship to the burner, regardless of the size and shape of the furnace. The shell becomes highly heated as the combustible mixture burns in the perfora- 35 tions, and therefore the heat is transferred therefrom to the furnace walls substantially without loss as radiant heat.

Other objects, advantages and novel features of the invention will be apparent from the following description when read in connection with the accompanying drawing, in which the single figure is a central section through a furnace having a burner embodying the invention.

The illustrated furnace comprises a jacketed 45 wall 10 having a side opening 12 communicating with a substantially cylindrical combustion space 14 which is connected at its upper end to a flue 16. The jacketed wall is adapted to contain water or other suitable heat transfer medium to conduct 50 heat to a room or other space to be heated.

The burner is constituted by a tube 18 extending substantially horizontally through the opening 12 and sealed therein by a suitable mounting member 20. Air is circulated through the tube 55 by a fan 22 under the control of an adjustable

disc 24 and is forced through a vaporizing nozzle 26 carried by the tube substantially at the vertical center of the furnace combustion space. As shown the nozzle comprises a porous refractory block having a series of longitudinal perforations therethrough and supplied with oil through a pipe 28 from any suitable gravity or pressure supply, all as more particularly disclosed and claimed in the copending application of Kemper P. Brace, Serial No. 145,706 filed June 10 1937.

It will be noted that a substantial length of the tube 18 is exposed in the furnace combustion space so that it will be heated during operation of the furnace. Preferably a plurality of heat 15 conducting fins 30 are formed inside the tube to increase the heating effect. With this arrangement air supplied to the nozzle will be heated to a high temperature to increase vaporization 20 of the fuel by reducing the cooling effect of the air thereby resulting in improved combustion.

In order to increase the heat supplied to the nozzle there is provided according to the invention, and to provide a size and shape of firebox 25 of maximum efficiency, as explained above, a perforated spherical shell or firebox 32 secured to the tube 18 substantially concentric with and spaced from the nozzle 26. Since a substantial part of the combustion occurs in the firebox 32 the temperature therein will be very high and a correspondingly high heating of the nozzle will be obtained. At the same time the walls of the firebox will be highly heated and will radiate or reflect heat to the nozzle.

Due to the high rate of vaporization obtained 35 by the present invention the capacity of the burner is increased to the maximum with highly efficient combustion conditions. While one embodiment of the invention has been shown and described in detail it is to be understood that 40 various other forms might be devised and it is not intended to limit the scope of the invention to the exact embodiment shown nor otherwise than by the terms of the appended claims.

What is claimed is:

1. In combination with a furnace, a liquid fuel burner comprising an elongated burner tube projecting into the furnace and terminating in the central portion thereof and adapted to conduct air for combustion into the furnace, a porous vaporizing nozzle carried by said tube having passages therethrough for air, means for supplying liquid fuel to said nozzle so that the fuel will be vaporized by air flowing through said passages, and a perforated shell surrounding the

- nozzle and adapted to reflect heat back to the nozzle.
2. In combination with a furnace, a liquid fuel burner comprising an elongated burner tube projecting into the furnace and terminating in the central portion thereof and adapted to conduct air for combustion into the furnace, a porous vaporizing nozzle carried by said tube having passages therethrough for air, means for supplying liquid fuel to said nozzle so that the fuel will be vaporized by air flowing through said passages, and a perforated substantially spherical shell surrounding the nozzle and adapted to reflect heat back to the nozzle, and heat conducting fins in the tube whereby air supplied to the nozzle will be heated.
3. A liquid fuel burner comprising an elongated burner tube having an air inlet opening at one end, a porous vaporizing nozzle at the other end of the tube having passages therethrough for air, means to supply liquid fuel to the nozzle so that the fuel will be vaporized by air flowing through said passages and a substantially spherical perforated shell carried by the tube surrounding and spaced from the nozzle. 5 10
